UNITED STATES PATENT OFFICE.

JOHN GELIN, OF CHICAGO, ILLINOIS.

NEWEL-POST CONSTRUCTION.

No. 904,195.

Specification of Letters Patent.

Patented Nov. 17, 1908.

Application filed May 18, 1908. Serial No. 433,454.

To all whom it may concern:

Be it known that I, JOHN GELIN, a citizen of the United States of America, and a resident of Chicago, Cook county, State of Illinois, have invented certain new and useful Improvements in Newel-Post Constructions, of which the following is a specification.

The main object of this invention is to provide an improved construction for ornamental wooden newel posts of stairways, which will considerably reduce the cost of such posts and in which the ornamentation is so applied that it will inclose the top of the post like a hood and will not be likely to open at the joints through irregular expansion and contraction due to atmospheric conditions. This object is accomplished by the device shown in the accompanying drawings, in which—

20 Figure 1 is a perspective view of the upper part of a newel post constructed according to this invention. Fig. 2 is a horizontal section of the same on the line 2—2 of Fig. 1. Fig. 3 is a perspective view, showing a modified application of this invention. Fig. 4 is a vertical section of the same, taken on the line 4—4 of Fig. 3.

In the construction shown, the body part of the newel post is hollow, being built up 30 of vertically disposed boards 5 fastened together and reinforced by the usual corner blocks 6. The ornamentation is applied in the form of a hood enveloping the upper end of the post and comprising a cap block 35 7 and side parts 8. The parts 8 are preferably formed of comparatively thin wood and are mitered where they meet each other at the corners of the post. The parts 8 are applied with their grain running parallel with 40 that of the post, so that the post as a whole has the general appearance of a solid, hand-carved post. This construction permits the parts 8 to be roughed out, then machine-carved, and afterwards applied to the face 45 of the post.

In Fig. 1 it is assumed that the joint 9 between the cap 7 and the parts 8 is a mitered joint similar to the joints between the adjacent edges of the parts 8. The structure shown in Figs. 3 and 4 will admit of either a mitered joint between the cap 7 and the side parts 8, or a joint such as is shown in Fig. 4. In Fig. 4 a part of the ornamentation is in the form of pieces of molding 10, but these pieces are applied to the

outside of the parts 8 and do not meet at the corners, so that they do not have mitered joints which tend to open through the unequal expansion or contraction of the adjacent parts.

60 Newel posts are usually ornamented by applying a cap block and covering a part of the upper end of the post by means of moldings which are comparatively thick and whose grain is horizontal while that of the post is vertical. In practice it is almost always the case that the moldings and the other parts of the post are differently seasoned, so that they are affected to a different degree by the presence or absence of moisture in the atmosphere. This, together with the fact that the grain of the molding is at right angles to the grain of the post, causes differences in the shrinkage or expansion of the parts, with the result that the ornamentation breaks away from the surfaces to which it is attached, opens at the joints, and warps and twists so as to leave unsightly cracks in the structure.

70 In the herein described construction, on the contrary, the grain of the side parts 8 of the ornamental hood is the same as that of the body of the post, and, as said parts are comparatively thin and are glued to the face of the body, they expand and contract 75 with it, and the opening of the joints is accordingly obviated. A further important advantage of the herein described construction lies in the fact that the side parts 8, when carved as in Fig. 1, may be machine-carved, as hereinbefore mentioned, and thereafter fitted upon the post, thus effecting a great saving over the present cost of 80 carved newel posts which, as usually constructed, must be carved by hand.

95 What I claim as my invention and desire to secure by Letters Patent is:—

1. A newel post, comprising a body part built up of wooden boards and an ornamental hood inclosing the upper end of said body and comprising a cap block and side parts, said side parts being formed of wood and meeting each other at the corners of the body, being fastened upon the adjacent boards of the body and laid with their grain 100 parallel with that of such adjacent boards.

105 2. A newel post, comprising a hollow body built up of wooden boards whose grain is vertical, and an ornamental hood inclosing the upper end of said body and comprising 110

a cap block and side parts, said side parts being formed of wood which is thin as compared with the boards of said body and meeting each other in mitered joints at the corners of said body, being fastened upon the adjacent boards of the body and laid with their grain vertical.

Signed at Chicago this 15th day of May 1908.

JOHN GELIN.
